UNITED STATES PATENT OFFICE

2,534,576

WINDOW DISPLAY PROTECTOR

Joseph Continenza, Stuart, Fla.

Application November 2, 1949, Serial No. 124,969

2 Claims. (Cl. 109—18)

1

The invention relates to a protective device adapted to be mounted in a store window and so designed as to protect articles displayed in the window against theft in the event of accidental or intentional breaking of the glass pane of said window.

An important object of the present invention is to provide a device of the type stated comprising a drop panel which normally is held in elevated position directly to the rear of the conventional glass pane utilized in a store window, but which will automatically, on breaking of the store window, fall instantaneously into position across the window aperture so as to protect against theft of articles displayed in the window.

Another important object is to provide a device as described which, after it has dropped into position, cannot be lifted except by the proprietor.

Summarized briefly, the invention includes a pair of upstanding guides that are mounted within the window directly to the rear of the conventional glass pane thereof, said guides having slidably mounted thereon sleeves rigidly connected to a drop panel extending fully across the window aperture. The drop panel is normally held in elevated position by connection to the shaft of an electric motor. However, by reason of a particular electrical circuit, the breaking of the store window energizes the motor and upon rotation of the motor shaft, the drop panel is disconnected and drops instantaneously into position across the window aperture so as to protect against theft of the articles. Latch devices carried by the drop panel engage the guides in the dropped position of the panel so as to prevent elevation of the panel.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings

Fig. 1 is a front elevational view of a store window, portions being broken away, the device constituting the subject of the invention being shown in front elevation.

Fig. 2 is a transverse vertical section through said store window and protective device.

Fig. 3 is an enlarged fragmentary elevational view of one of the latch devices.

Fig. 4 is a section on line 4—4 of Fig. 3.

2

Fig. 5 is a vertical section through the connection of the drop panel to the actuating motor.

Fig. 6 is a diagram of the electrical circuit embodied in the invention.

Referring to the drawings in detail, the reference numeral 5 designates an ordinary store window, such as the window of a jewelry store or similar establishment, said store window being equipped with the conventional glass pane 6 and display stands or shelving 7.

In accordance with the present invention, there are mounted on the floor of the window, adjacent opposite sides of the window aperture, feet 8 in which there are positioned the lower ends 10 of vertically extending guides 9 the upper ends of which are positioned in sockets 11 secured to the ceiling of the store window, so that said guides 9 in effect comprise a vertically disposed slideway on which the drop panel is mounted for vertical sliding movement. Said drop panel comprises a rectangular frame 11 extending around and secured to the solid panel 12, the opposite sides of the frame 11 being rigidly secured to sleeves 13 by welds 14 or similar means, said sleeves 13 being mounted for sliding movement upon the guide rods 9 and being equipped at their lower ends with the rubber bumpers 15 whereby on dropping of the drop panel, the shock of falling will be absorbed.

To the upper edge of the drop panel, intermediate the ends of said panel, there is rigidly secured the slotted bracket 16, which is secured to the drop panel by means of rivets 17 or the like, said slotted bracket 16 being integral or otherwise rigid with the upwardly extending stud 18 threaded so as to be received in the depending threaded socket 19 having the reduced upper extension 20 connected by a set screw 21 to the shaft 22 of an electric motor 23 bolted to the ceiling of the store window.

Thus, assuming that the motor 23 is suddenly energized, said motor will rotate the threaded socket 19 at high speed so as to cause separation of said socket from the threaded stud 18 of the drop panel and the drop panel will immediately fall into position across the window aperture.

Assuming that the drop panel has fallen into position across the window aperture so as to protect against theft of the articles displayed within the window, it is held against elevation from its drop position by reason of a latch arrangement which includes the longitudinal series of teeth 24 formed on each of the guide rods 9 intermediate the ends of said guide rods. Engageable with any of the teeth 24 is the beveled inner

edge 25 of a yoke 26 rigid with the arm 27 formed integral with a transversely extended sleeve pivoted on pin 28, said arm 27 having the extension 29 adapted to be engaged under a keeper 30 pivoted at 31 to the frame 11 of the drop panel. The pivot pin 28, it may be noted, is mounted upon a bracket 32 rigidly secured in any suitable manner to each corner of the drop panel.

When the drop panel is in its elevated position, and the device is positioned ready for use in the event of breaking of the glass pane 6, the keeper 30 is moved to the full line position illustrated in Figs. 3 and 4 so as to be out of engagement with the extension 29 of the pivoted latch. As a result, assuming that the motor 23 is energized so as to cause instantaneous dropping of the drop panel 12, the dropping of the panel 12 to its lowermost position causes the latch 27 to be positioned where it will engage any of the teeth 24 should anyone attempt to elevate the drop panel from the lowered position thereof. As a result, the latch 27 will be positioned as in the full lines illustrated in Fig. 3, and anyone attempting to elevate said panel will be unable to do so.

However, at such time as the store owner again elevates the drop panel, it is necessary only that he adjust the pivoted latch to the dotted line position illustrated in Fig. 3 and engage it under the keepers 30, whereupon the drop panel can be elevated to the position illustrated in Fig. 1 after which the keepers 30 are again adjusted away from the extensions 29 so as to again position the drop panel ready for use.

It will be understood that the pivoted latches 27 will be so located as to be inaccessible to someone outside the window.

In Fig. 6 I have illustrated an electrical circuit well adapted to serve the purposes of the present invention. An endless electrically conductive tape 33 extends throughout the marginal portion of and is adhesively secured to the glass pane 6, as best seen in Fig. 1. This endless electrically conductive tape 33 is in circuit with a relay 34 and with an electrical transformer 35, and said circuit is powered through leads 36 extending from the ordinary house supply. Thus the electrically conductive tape 33 is continuously energized so as to hold the relay 34 energized.

As long as the relay 34 is energized, it attracts and holds open a switch 37 that is in circuit with the motor 23. Thus, the motor 23 is normally not energized and by reason of its threaded connection with the drop panel (see Fig. 5) the drop panel is held elevated under normal conditions. However, assuming that a burglar breaks the glass pane 6 for the purpose of removing articles displayed within the store window, the breaking of the glass pane 6 severs the tape 33 breaking the circuit to the relay 34. As a result, switch 37 instantaneously closes, closing a circuit to and including the house supply and the motor 23. The motor upon going into operation rotates the shaft 22 at high speed so as to instantaneously break the threaded connection between the socket 19 and the stud 18. The panel 12 drops into position across the window aperture, so as to protect against theft of the articles displayed within the window. All this takes place, of course, within the space of so short a time as to prevent the person breaking the window from removing any of the articles displayed.

The relay 34 and the electrical transformer 35 can be suitably housed within a box 38 se-

cured to the ceiling of the store window. It may be noted, in this connection, that it is of course possible for the electrical circuit illustrated in Fig. 6 to also include a visible or audible burglar alarm of the conventional type, and it is believed that this is so obvious as not to require special illustration, since it is well within the skill of those experienced in the art to include such an alarm mechanism with the device illustrated and described herein.

I believe the advantages of a device constructed as illustrated and described will be readily apparent. For example, jewelry stores are continuously faced with the problem of thievery caused by someone breaking the window of the store and stealing all or a valuable part of the jewelry displayed within the window. In most cases, jewelry store windows and other windows in which valuable material is displayed are equipped with alarm devices, many of which include tapes such as illustrated at 33 herein. However, these alarm devices serve solely to advise protective agencies of the fact that the window has been broken, or cause sounding of a burglar alarm on the premises, but in no case do they prevent the thief from stealing the articles themselves and disappearing before the arrival of the police. In the present instance the possibility of theft is fully eliminated, since the breaking of the window itself electrically connects the motor with the source of electricity, and the drop panel instantaneously, to all intents and purposes, drops into position across the window aperture so as to prevent theft of any article within the window. The latch device is illustrated in Figs. 3 and 4, engaging the teeth 24 in the dropped position of the panel to prevent elevation of the panel.

It is to be understood that different types of store windows, different ceiling elevations, and other factors might require different methods of mounting the motor 23, housing 38, and upper brackets 10 of the guide rods 9. For example, most store ceilings are too high to permit a motor to be mounted as shown in Fig. 1, and this illustration is purely for the purpose of showing that a motor is fixedly mounted above the drop panel. In most cases, this reason, and also the desirability of preventing vibration and insuring proper operation of the panel, would undoubtedly make it more advisable to provide a bracket which will serve as a mounting for the motor, energizer unit or relay housing, and also as a means to which can be attached the upper ends of the guide rods 9. The formation and location of this bracket would, of course, depend upon the particular window formation, and it is mainly important that the upper ends of the guide rods, the motor disposed between said guide rods, and the energizer unit all be stationarily mounted in a proper position in a manner to insure proper operation of the device and to meet any special conditions dictated by the particular window structure and by the store owner.

5 What is claimed is:

1. A window display protective device including a pair of upstanding spaced guides mounted within a window, a iron panel extending between said guides and slidably mounted thereon, a motor mounted above said drop panel, a threaded connection between the motor and drop panel and normally engaging the panel so as to hold the panel elevated, means actuated by breaking of a window and adapted to energize the motor so as to break the threaded connection for drop-

ping of the panel, and latch devices inter-engaging between the panel and guide rods for preventing elevation of the panel from its dropped position.

2. A window display protection device including a pair of upstanding spaced guides adapted for mounting in a store window adjacent the glass pane thereof, sleeves mounted for sliding movement upon said guides, a solid panel extending between and rigidly connected to the sleeves, a motor mounted above the drop panel, a threaded socket rotatable with the shaft of said motor, a threaded stud carried by the upper end of the drop panel and normally engaged in the socket, whereby on rotation of the motor shaft the socket will disengage from the stud to permit dropping of the panel, an electrically conductive tape mounted upon the window, means in circuit with the tape and normally preventing energizing of the motor, whereby on breaking of the pane and tape the motor will be energized, and

latch devices inter-engaging between the panel and guide rods in the dropped position of the panel to prevent elevation thereof from said dropped position.
